UNITED STATES PATENT OFFICE

2,378,842

METHOD OF MAKING HUB STRUCTURES

Archibald Graham Forsyth, Cheam, England, assignor to The Fairey Aviation Company, Limited, Hayes, England

Original application November 3, 1942, Serial No. 464,369. Divided and this application December 27, 1943, Serial No. 515,766

2 Claims. (Cl. 29—156.8)

This invention relates to a propeller hub. More particularly the invention relates to a method of constructing a propeller hub for variable pitch propellers. This application is a division of my copending application Serial No. 464,369, filed November 3, 1942.

Primarily because of space requirements and the complexity of the mechanism required for changing the pitch of variable pitch propeller blades, the hub structures heretofore employed have been complicated in nature and difficult of manufacture. In particular they have required a great number of machining operations and consequently their manufacture, particularly in wartime, has not been as rapid as is desired. It is a principal object of the present invention to avoid these drawbacks.

The invention has as another object the provision of a method of making a simply designed hub for variable pitch propellers which hub is comprised primarily of standard tubular pieces and which with a few machining and brazing or welding operations can readily be assembled in final form. In accordance with the invention, the construction is so designed as to enable its use in arrangements embodying one or more sets of variable pitch propellers.

Another object of the invention resides in an improved method of constructing a hub unit for variable pitch propellers.

A further object of the invention resides in a method of making a hub structure which requires less material than heretofore necessary. Consequently this effects a great saving of critical materials.

These and other objects of the invention will become more apparent in the following description and claims when read in conjunction with the accompanying drawings in which:

Figure 1 is a side elevation of a hub construction embodying the invention;

Figure 2 is a front view;

Figure 3 is an enlarged detail view taken on the line 3—3 of Figure 1;

Figure 4 is a vertical section taken on the line 4—4 of Figure 5 through the principal tubular member forming a part of the hub structure;

Figure 5 is a sectional view taken on the line 5—5 of Figure 4;

Figure 6 is a section taken on the line 6—6 of Figure 4;

Figure 7 is a view similar to Figure 4 after additional machining operations have been performed and taken on the line 7—7 of Figure 8;

Figure 8 is a sectional view taken on the line 8—8 of Figure 7;

Figure 9 is a section taken on the line 9—9 of Figure 7;

Figure 10 is a sectional view of a tubular section employed as a part of the hub construction;

Figure 11 is a similar view to Figure 10 after an additional machining operation has been made;

Figure 12 is a horizontal section of the hub construction after partial assembly;

Figure 13 is a sectional view taken on the line 13—13 of Figure 12;

Figure 14 is a vertical section through a tubular member which after machining and assembly forms a sleeve for the propeller drive shaft;

Figure 15 is a similar view to Figure 14 after machining operations have been completed;

Figure 16 is an end view of the structure shown in Figure 15;

Figure 17 is a horizontal view through the assembled hub structure; and

Figure 18 is a section taken on the line 18—18 of Figure 17.

As illustrated, the invention will be described in connection with a propeller hub adapted to receive two aligned propeller blades, the pitch of each blade being capable of variation simultaneously. With reference to Figures 1 and 2, the hub structure is comprised of a main tubular portion 2, the opposite ends of which are adapted to receive propeller blades 4 in any suitable manner which will enable the propeller blades to rotate about their longitudinal axes and also to retain the propeller blades securely in place during rotation of the hub structure when driven by the motor 6. For example, the blades may be supported in the hub in a manner similar to that illustrated and described in my copending application, Serial No. 459,691, filed September 25, 1942.

The tubular portion 2 is provided with circular openings on its forward and rearward surfaces, 45 which openings are aligned on the rotational axis of the hub structure. In these openings is disposed a tubular member 8 which is welded to the abutting surfaces of the circular openings so as to constitute an integral part of the hub structure. The tubular member 8, when the device is assembled, is adapted to receive a propeller drive shaft which is keyed thereto as will be later described.

Spaced outwardly from the rotational axis of 55 the hub structure, and disposed tangentially with

respect to the main tubular portion 2 and on opposite sides thereof, are two smaller tubular portions 10 and 12. As shown in Figure 3, these smaller tubular portions 10 and 12 are rigidly secured to the wall of the main tubular portion 2 about openings cut in the wall of the tubular portion 2. These smaller tubular portions 10 and 12 themselves are provided with openings which when the smaller tubular portions are secured to the main tubular portion 2, are in registry with the openings in the wall of the main tubular portion 2. The forward ends of the smaller tubular portions 10 and 12 are closed respectively by capped members 14 and 16 (see Figures 1 and 3) and the tubular member 8 is also closed by a cap member 18 in a similar fashion.

As described in several of my previous applications, such as application Serial No. 459,691, filed September 25, 1942, the base of each propeller blade is provided with a ring gear 20 adapted to be engaged by a worm gear 22, the turning of which effects rotation of the propeller blade about its longitudinal axis and thus causes a change in the pitch of the propeller.

In accordance with the present invention, the base of each propeller blade with a ring gear 20 rigidly secured thereto, is housed within an end of the main tubular portion 2 in such a manner that the ring gear 20 extends outwardly into the opening between the main tubular portion 2 and the smaller tubular portion 10 (see Figure 3). Here the ring gear 20 is engaged by a worm gear 22 mounted on shaft 24 supported by bearings 26, 26' within a smaller tubular portion 10 or 12.

The shafts 24 in each of the smaller tubular portions 10 and 12 extend rearwardly from these portions and through closure plugs 27, and their rear ends each have a pinion such as 28, 28' secured thereto. As shown in Figures 1, 2 and 3 these gear pinions 28, 28' are adapted to be engaged by a ring gear 30 driven by an electric or hydraulic motor, or by other means (not shown), controlled by the pilot.

It will be apparent that upon rotation of the ring gear 30 in either direction, the pinions 28, 28' will be rotated, thus turning the worm gears 22 and, through the ring gears 20, rotating the propeller blade roots about their longitudinal axes. This simultaneously changes the pitch of the propeller blades. Obviously, other operative mechanisms for simultaneously engaging and driving the gear pinions 28, 28' may be employed. As an example, reference may be made to my previous application, Serial No. 449,123, filed June 30, 1942.

Figures 4 to 18 inclusive illustrate respectively the successive steps which may be employed in making the hub structure illustrated in Figures 1, 2 and 3, and which has just been described.

With reference to Figures 4, 5 and 6, the main tubular portion 2 is preferably constructed of a piece of steel tubing or the like. Advantageously the tubing may be made of steel plate bent to form a cylinder with the abutting edges welded. The central opening or cross hole 36 is bored in the main portion 2 and this opening on one side of the tubing 2 is provided with a small notch 38, the purpose of which will be described hereinafter.

The next step in the fabrication of the hub structure is illustrated in Figures 7, 8 and 9. This step comprises cutting or milling openings 38 and 40 on opposite sides of the main tubular portion and spaced equidistantly from the horizontal axis of the main tubular portion 2. Be-

cause the main tubular portion 2 is circular, and these openings 38 and 40 are cut with a cylindrical cutting tool, the openings will be oval in shape as indicated clearly in Figure 8.

The next step in the operation is the fabrication of the small tubular portions 10 and 12. This step is shown in Figures 10 and 11. These small tubular portions are formed from steel tubing of smaller diameter. A cylindrical cutting tool is employed to cut the openings 46 indicated in Figure 11.

The tubular member 8 (see Figures 1 and 3) is also constructed of a section of tubing, the walls of which are fairly thick. Such a section of tubing is illustrated in Figure 14. By suitable milling and turning operations, this section of tubing assumes the shape illustrated in Figure 15 from which it will be noted that one end 48 of the tubular member 8 has a greater diameter than the adjacent portion 50. The end 48 has a beveled opening 52 and the end of the portion 50 also has an enlarged central opening 54. A small threaded opening is provided in the wall of the tubular member 8 for the insertion of a knobbed screw 56. The inner surface of the tubular member 8 is provided with splines 58.

In assembling the various parts, the tubular member 2 is first heated to expand it sufficiently to permit the tubular member 8 to be inserted through the circular cross openings 36. (See Figures 17 and 18.) The tubular member 8 is disposed so that the knob of the screw 56 is engaged in the notch 38. The outside contacting edges of the tubular portion 2 and tubular member 8 are then brazed or welded such as at 60. Weld inserts 62 may also be used for strengthening purposes. The knobbed screw in the notch 38 also strengthens the assembly and prevents rotation of tubular portion 2 with respect to tubular member 8 in the event of weakening of the weld lines or shearing of such lines.

The small tubular members 10 and 12 are now brazed or welded to the main tubular portion 2 as indicated in Figures 12 and 13. The brazing or welding is accomplished so that the openings 46 in the small tubular portions register with the openings 40 in the main tubular portion 2. This securing is accomplished preferably by welding.

Screw threads 32 and 34 are then cut in the inner surface of the tubular portion 2 at each end. These screw threads are adapted to receive a socket (not shown) for the propeller blades. Threads are also cut in the front opening 54 of tubular member 8 to receive the closure member 18. The inner surfaces of each end of each of the small tubular members 10 and 12 are then tapped to provide the threads 42 and 44. Finally, the assembled hub structure is plated such as with cadmium plate or the like.

The hub structure fabricated in the manner described may now be assembled for operation as illustrated in Figures 1, 2 and 3. The assembly operation comprises merely disposing the hub structure so that the tubular portion 8 is splined by keys 51 to a propeller drive shaft (not shown) after which the cap 18 is disposed in the threaded end opening 54. The propeller blade roots are then disposed in opposite ends of the main tubular member 2 so that the ring gears 20, rigid with the blade roots, are in a position to engage the worm gears 22 which are disposed in the smaller tubular portions 10 and 12 in the manner illustrated in Figure 3. The cap members 14 and 16 for the front ends of the smaller tubular

members 10 and 12 are then inserted in place and the assembly is thus complete.

While the hub structure described is only adapted to support two propeller blades, it is obvious that several of such hub structures may be employed, as for example when two sets of propellers are mounted on coaxial propeller drive shafts so as to drive the sets in contra rotating directions.

Obviously changes in form and structure, and in the method of fabrication and assembly may be made without departing from the inventive concept. The invention is to be limited only to the extent indicated in the following claims.

I claim:

1. The method of making a hub for variable pitch propellers which comprises first cutting aligned centrally disposed, transverse openings in a cylindrical tubular body, second, milling cut-outs of semicircular cross section in said tubular body on opposite sides thereof and tangentially with respect to said body and along lines spaced equidistantly from and parallel to the axis of said aligned openings, third, forming a larger tubular member having an enlarged end and a central cylindrical portion slightly larger than the diameter of such aligned openings in said body, fourth, heating said body and forcing the larger tubular members through said aligned openings transversely of said tubular body, fifth, joining said tubular body and larger tubular member together after said tubular body is cooled, sixth, forming a pair of small tubular members with arcuate cut-outs in one wall thereof, seventh, joining said small tubular members respectively in said cut-outs of said body with the cut-outs of said small

members abutting respectively a cut-out in said body thereby forming communicating openings between the interiors of said small tubular members and the interior of said body.

5. The method of making a hub for variable pitch propellers which comprises in first, cutting aligned centrally disposed, transverse openings in a cylindrical tubular body, second, milling cut-outs of semicircular cross section in said tubular body on opposite sides thereof and tangentially with respect to said body and along lines spaced equidistantly from and parallel to the axis of aligned openings, third, forming a larger tubular member having an enlarged end and a central cylindrical portion slightly larger than the diameter of said aligned openings in said body, fourth, heating said body and forcing the larger tubular members through said aligned openings transversely of said tubular body, fifth, joining said tubular body and larger tubular member together after said tubular body is cooled, sixth, forming a pair of small tubular members with arcuate cut-outs in one wall thereof, seventh, joining said small tubular members respectively in said cut-outs of said body with the cut-outs of said small members abutting respectively a cut-out in said body thereby forming communicating openings between the interiors of said small tubular members and the interior of said body, eighth, threading the inner surfaces of said smaller tubular members at each end, and ninth, threading the inner surface of said larger tubular member at the end opposite said enlarged end.

35 ARCHIBALD GRAHAM FORSYTH.
